UNITED STATES PATENT OFFICE.

GEORGE J. PFEIFFER, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS.

BOBBIN STRIPPER.

Application filed March 22, 1922. Serial No. 545,864.

To all whom it may concern:

Be it known that I, GEORGE J. PFEIFFER, a citizen of the United States, residing at Providence, in the county of Providence and 5 State of Rhode Island, have invented a new and useful Bobbin Stripper, of which the following is a specification:

This invention relates to a bobbin stripper of the general type disclosed in my cop- 10 pending application, Serial No. 536,536 filed February 14, 1922. In this machine, the bobbins are fed singly to gripping jaws from which they are removed longitudinally by the combined action of pushing and 15 pulling elements which successively engage and advance the bobbins between the jaws.

It is the principal object of my present invention to improve the construction and 20 operation of the withdrawing or pulling elements of such a machine, adapting these elements particularly for use with bobbins having conical heads.

In the preferred form, I provide a pair 25 of jaws which are regularly reciprocated and I also provide means for raising the jaws above a bobbin on the inoperative stroke, said jaws being lowered and forced against the sides of the conical head of the bobbin at the beginning of the operative stroke.

30 My invention further relates to arrangements and combinations of parts which will be hereinafter described and more particularly pointed out in the appended claims.

A preferred form of my invention is 35 shown in the drawings, in which—

Fig. 1 is a plan view of a bobbin stripper embodying my improvements;

Fig. 2 is a detail sectional elevation taken along the line 2—2 in Fig. 1;

40 Fig. 3 is an enlarged plan view of a cam shown in Fig. 1;

Fig. 4 is an enlarged plan view of the bobbin gripping jaws and the operating devices therefor;

45 Fig. 5 is a side elevation, partly in section, taken along the line 5—5 in Fig. 4;

Fig. 6 is a sectional end elevation taken along the line 6—6 in Fig. 4; and

50 Figs. 7 and 8 are side elevations of the parts shown in Fig. 4, illustrating the operation of the mechanism.

Referring particularly to Fig. 1, the bobbin stripper therein shown comprises a frame 10 supporting a pair of rotating

shafts 11 and 12. Bobbin holding members 55 or discs 13 and 14 are mounted on the shafts 11 and 12 and these shafts are intermittently rotated by means of a star wheel 15 and a one-toothed locking pinion 16, the latter being mounted on a shaft 17 having a spiral 60 gear connection with a crankshaft 18 connected by a gear 19 and pinion 20 to a driving shaft on which is mounted a driving pulley 21.

The shaft 11 rotates in fixed bearings and the shaft 12 is mounted in a bearing which is angularly movable about a pivot or stud 22 at the left hand side of the machine. The shaft 12 and disc 14 are yieldingly pressed toward the shaft 11 and disc 13 by a lever 65 23 on a short shaft 24 mounted in bearings on the side of the frame 10. An arm 25 on the shaft 24 is connected by a link 26 (Fig. 2) to a lever 27 mounted on a fixed pivot 28 and actuated by a cam 30 on the shaft 17. 70 As the high point of the cam engages the upper end of the lever 27, the rod 26 is moved to the right in Fig. 2 and the arm or lever 23 is withdrawn from the shaft 12. At other times the spring on the rod or link 26 causes the lever 23 to yieldingly engage 75 the shaft 12.

A plunger 31 (Fig. 1) is mounted to slide between the shafts 11 and 12 and moves the bobbin held by the discs 13 and 14 longitudinally to partially eject the bobbin from between the discs. The plunger 31 is connected by a link 32 to an arm 33 mounted on a cross shaft to which is also secured an arm 34 connected by a link 35 to a crank 80 pin 36.

The parts are so timed that the shaft 12 and disc 14 will be pressed inwardly at the moment when the plunger 31 is moving forward to partially eject the bobbin.

The parts thus far described are set forth in greater detail in my prior application, above identified, and in themselves form no part of my present invention.

In order to secure the desired timed relation between the cam 30 and the plunger 31, I mount the cam 30 (Fig. 3) loosely on the shaft 17 between collars 37 and 38. The collar 37 remains in fixed position on the shaft 17 and the collar 38 is provided with 100 means for removably securing the same to the shaft in fixed position when desired.

The cam 30 is provided with a toothed or

serrated flange 40 and the collar 38 is provided with a similar serrated flange 41. By slightly loosening the collar 38 and moving the same to the left, the cam 30 may be set in any desired angular position and will be retained therein by the co-operation of the teeth of serrations on the flanges 40 and 41.

As shown in Fig. 3, the teeth on the flange 41 extend over a small portion only of the 10 circumference while the teeth on the flange 40 may extend entirely around the flange. The cam 30 may thus be very accurately positioned and will be securely retained in any position.

15 The plunger 31 acts to partially eject the bobbin from between the discs 13 and 14 but the longitudinal withdrawal of the bobbin is completed by a pair of gripping members or jaws 42 (Fig. 4) which are 20 pivoted on studs 43 in a block 44 which, in turn, is mounted to swing about a horizontal pivot 45 in a bracket 46 (Fig. 5) secured to a slide 47.

The slide 47 is mounted in guide-ways 25 48 and is connected by a link 49 to the crankshaft 18 (Fig. 1). The slide and gripping members are thus regularly reciprocated in timed relation to the movements of the discs 13 and 14 and the plunger 31.

30 An important feature of my invention relates to the devices by which the gripping members 42 are controlled and directed. For this purpose I provide a cam roll 50 (Fig. 4) mounted on a stud 51 projecting 35 from one of the gripping members 42. A cam plate 52 is provided with a stud 53 which is pivotally supported in bearings 54 in a bracket 55 secured to one of the guide-ways 48. A spring 56 is mounted on the 40 stud 53 and engages one of the bearings 54 at one end and a collar 57 on the stud 53 at the other end. The cam plate 52 is thus normally held yieldingly in its lower position and against the upper surface of the 45 guide-way 48, as shown in Fig. 5.

As the slide 47 moves to the left and approaches the stripping or holding discs 13 and 14, the roll 50 engages the upper surface of the cam plate 52 and raises the gripping members as shown in Fig. 7, so that they pass over the end of the bobbin B which has been partially ejected from between the discs 13 and 14. At the end of the inward or inoperative stroke, the roll 50 passes beyond the cam plate 52 and the members 42 move to their lower operative position at the sides of the bobbin B.

Upon the return or operative movement of the slide 47, the cam roll 50 passes idly 60 under the plate 52, swinging the same upward about its pivot 53.

Each member 42 is also provided with a roll 60 and a cam plate 61 is provided at the inner side of each guide-way 48. Upon 65 their inoperative or inward movement, the

rolls 60 are raised above the plates 61 but upon their return or operative movements they are engaged by the plates 61, which force the members or jaws 42 inward against the head of the bobbin B. The 70 gripping faces of these jaws 42 are preferably conical and concave so as to firmly engage and grip the conical head of a bobbin of the type engaged in Figs. 7 and 8. A spring 62 (Fig. 4) is disposed between the 75 gripping members 42, forcing them yieldingly apart when not positively moved inward by the cam plates 61.

It has been heretofore considered impracticable, if not impossible, to successfully remove weft from bobbins having conical heads, as the weft clings very tightly to this type of bobbin and it has been found very difficult to secure a firm grip on such a bobbin. With my improved construction, however, the bobbin is firmly gripped between the members 42, and the final withdrawal of the bobbin from the stripping discs is easily accomplished. This method of stripping a bobbin by partially removing the waste yarn therefrom, grasping that portion of the bobbin thus uncovered and applying force thereto for the purpose of completing the stripping operation is believed to be broadly new and within the 95 scope of my invention.

Having thus described my invention and the advantages thereof, I do not wish to be limited to the details herein disclosed otherwise than as set forth in the claims, but 100 what I claim is:—

1. In a bobbin stripper, stripping devices, and means to withdraw a bobbin longitudinally from between said devices, said means comprising a pair of bobbin gripping members, means to reciprocate said members, means to yieldingly separate said members, means to hold said members above the bobbin when moved in one direction, and means to cause said members to descend and to 110 approach each other and grip the bobbin when moved in the opposite direction.

2. In a bobbin stripper, stripping devices, and means to withdraw a bobbin longitudinally from between said devices, said means comprising a pair of bobbin gripping members, means to reciprocate said members, means to raise said members above the bobbin on their inoperative stroke, said members being permitted to move downward at the end of the inoperative stroke, and means to force said members positively toward each other to grip the bobbin during the withdrawal of the bobbin thereby from between said stripping devices.

3. In a stripper for bobbins having conical head portions, in combination, stripping devices, a pair of bobbin gripping members having conical, concave gripping faces, means to reciprocate said gripping

members, and means to force said members against the conical head portion of said bobbin, to grip and hold said conical head portion during the operative movement of 5 said members relative to said stripping devices.

4. In a bobbin stripper, stripping devices, and means to withdraw a bobbin longitudinally from between said devices, said members comprising a pair of bobbin gripping members, means to reciprocate said members, a cam plate to hold said members in raised position on their inoperative movement, and additional fixed cam plates to 15 force said members against the bobbin during their operative movement.

5. In a bobbin stripper, stripping devices, and means to withdraw a bobbin longitudinally from between said devices, said means 20 comprising a pair of bobbin gripping members, means to reciprocate said members, one of said members having a roll, a pivoted cam plate engaging said roll to raise said members during their inoperative movement, a pair of fixed cam elements and a 25 roll on each of said members engaging said cam elements to force said members against the bobbin during the operative movement of said members.

6. In a bobbin stripper, a pair of rotatable stripping jaws, shafts for said jaws, one of said shafts being mounted for lateral movement, and means to move said shaft laterally, said means including an actuating

shaft, a cam loosely mounted on said shaft, 35 means to prevent axial movement of said cam in one direction, and a collar fixed on said shaft at the opposite side of said cam, said collar and said cam having co-operating serrated portions by which said cam 40 may be held in a selected angular position on said shaft.

7. A stripper for bobbins having conical head portions comprising means to give a cone bobbin an initial advance movement, 45 means engaging the waste yarn on the bobbin and preventing movement thereof with the bobbin, devices firmly engaging the conical portion of the bobbin thus uncovered, and means to move said devices to 50 complete the advance movement of said bobbin.

8. In a stripping machine for cone bobbins, stripping means, means to initially advance a bobbin, a pair of bobbin gripping 55 members having concave conical bobbin engaging faces, means to move said members toward said bobbin and to cause said members to engage the conical head portion of said bobbin uncovered by the initial advance movement thereof, and means to thereafter move said gripping members and bobbin longitudinally to complete the stripping of the waste therefrom.

In testimony whereof I have hereunto 60 affixed my signature.

GEORGE J. PFEIFFER.
